UNITED STATES PATENT OFFICE.

JOHN BRUNEAU, OF CLICHY, PARIS, FRANCE.

VAPOR-BURNER.

No. 874,735.

Specification of Letters Patent.

Patented Dec. 24, 1907.

Application filed May 26, 1906. Serial No. 318,972.

To all whom it may concern:

Be it known that I, JOHN BRUNEAU, a citizen of Sweden, residing at 6 Rue de Paris, Clichy, Paris, France, have invented new 5 and useful Improvements in Vapor-Burners, of which the following is a specification.

It is heretofore known to employ annular vaporizers in illuminating and heating apparatus working with liquid fuel, but these 10 vaporizers suffer from the disadvantage of not being kept uniformly hot in case the flame flickers owing to a draft or some other cause, the vaporization as a result being irregular and imperfect.

15 The present invention having for its object to overcome this inconvenience consists in arranging within the annular vaporizer a superheating chamber which becomes exposed to an intense heat since the annular 20 vaporizer draws the heat up through the inner space containing the superheater. Should the flame by a draft or other influence be caused to flicker, this will exert no detrimental influence on the superheater, the latter holding sufficient heat to keep the fuel 25 vaporized.

The invention is illustrated in the accompanying drawing where Figure 1 shows the device here referred to in vertical section.

30 Fig. 2 is a modification.

1 is the annular vaporizer which is connected with the supply-pipe 2 for the fuel and with a superheater 5 arranged within the vaporizer and communicating with the discharge-nozzle 4 by means of a pipe 3. To 35 prevent fuel which is not completely vaporized from entering the superheater, the connecting pipe 6 between the latter and the vaporizer 1 preferably extends to the upper end of the vaporizer. As a result of this 40 arrangement the vaporizer must be completely filled with fuel before the latter can flow into the superheater which will conse-

quently contain completely vaporized fuel only. The pipe 3 may moreover extend to 45 the upper end of the superheater 5.

In the form shown in Fig. 2 the superheater 5 is itself formed into a connecting pipe 6 communicating with the vaporizer 1 and then passing directly into the pipe 3 50 leading to the burner. This construction is much more simple than the former though not so efficient. It may be evident that the invention is not limited to the forms illustrated which may be varied in many ways 55 without departing from the principle of the invention, the main feature of which consists in the arrangement within the annular vaporizer of a superheater, communicating with the said vaporizer and the discharge 60 nozzle.

Having now particularly described and ascertained the nature of my said invention and in what manner the same is to be performed, I declare that what I claim is: 65

In a vapor burner a closed vessel of annular cross-section connected with the oil supply and arranged centrally above the burner, a second closed vessel of cylindrical cross-section of smaller diameter than the inner 70 space of the annular vessel centrally inserted in the latter, a pipe of communication starting from the bottom of said cylindrical vessel and reaching up into the annular space to near the top of the annular vessel, a feed 75 pipe leading to the burner from a point near the top of the cylindrical vessel, substantially as described.

In testimony whereof I have signed my name to this specification in the presence of 80 two subscribing witnesses.

JOHN BRUNEAU.
